UNITED STATES PATENT OFFICE.

ALFRED E. WALKER, OF OKLAHOMA, OKLAHOMA, ASSIGNOR TO MAURICE A. PORTER,
OF OKLAHOMA, OKLAHOMA.

WELL.

1,177,070.

Specification of Letters Patent. Patented Mar. 28, 1916.

Application filed September 5, 1913. Serial No. 788,288.

To all whom it may concern:

Be it known that I, ALFRED E. WALKER, a citizen of the United States, residing in the city, county, and State of Oklahoma, have 5 invented a certain new and useful Well, of which the following is a specification, reference being had to the accompanying drawing.

This invention has reference to the art of 10 wells, and especially to water-wells, and consists in providing means for permanently and successfully harnessing or holding in check those various elements that prevent the natural and free course of incoming 15 flow of the water into the well. For instance, to be more specific, the invention contemplates the holding back of the quick-sands and other such like elements through 20 mechanical instrumentalities which may be applied and removed at will for any purpose necessary in constructions of this character.

It is an object of the invention to provide 25 a simple, inexpensive and practical construction, adapted for forming a well and retaining certain elements in place or under control during formation.

In order to use the invention, any suitable 30 construction or constructions may be adopted within the purview of the inventive concept, so long as the undesirable elements are held in check, positively, and to this end, the sheet of drawings, accompanying and 35 forming a part of this specification, illustrates one of the convenient forms or embodiments of said invention.

On this sheet of drawings, Figure 1 illustrates 40 in elevation a section of the well completed. Fig. 2 is a section of a practical filtering device. Fig. 3 is an enlarged section of one of the inlet nipples. Fig. 4 is a detail enlargement of another nipple showing 45 means for capping the same during the construction of the well to hold back sands and other substances, and, Fig. 5 is a front elevation of one of the nipples, showing the same capping retarding bars.

In the several illustrations, similar characters of reference indicate similar parts. 50 After the usual digging necessary for creating an aperture for a well, and which digging is carried to the quick sand. I deposit a base, having an opening, preferably 55 central, upon which I form a suitable casing, in any suitable manner, for instance of

brick, metal or concrete, said casing being indicated by 6, the lower end whereof being formed into filtering chambers 7 and 8, preferably by bifurcating the lower end of the wall, and introducing into said bifurcation a wall 9, that rising from the bottom nearly to the top 10 of the bifurcation forms two communicating chambers, adapted to contain an elongated body of filtrant through which the incoming water may percolate. As digging proceeds, this structure, together with the upper casing wall 6 is adapted to gravitate with the base 11, until the latter is deposited upon bed rock, and during the descent, additional wall may be 60 created upon the wall 6 to finally finish the casing. When the base reaches bed rock, the opening (not shown) is closed, or sealed. The annulus formed by the bifurcated filtering chamber is filled with suitable filtering 65 material lying on either side of said wall 9.

In the outer wall 12, of the filtering chamber, using as many as may be desirable to get as much water as possible into the well, are nipples 13 having a flange 14, through 70 which are passed perpendicularly, a number of rods 15, preferably such as will not corrode, and these are designed to prevent the filtrant in the chamber from escaping. In the inner wall 16, of the filtering chamber, there may be located a suitable number 75 of nipples 17 that are provided with reducing nipples 18 that are externally screw-threaded as at 19, to receive caps 20, while well construction is in process, and when 80 the well is finished, and the hole in the base sealed against incoming of the sands, then these caps may be removed, and in their stead may be applied any suitable sort of 85 filtering devices, such, for instance, as is shown, and which comprise a chamber, preferably in the form of a globe 21 having an interiorly screw threaded nipple 22 to take over the nipple 18. This filtering device is also provided with an outlet nipple 90 23 through the body of which are passed rods 24, and, if desired, rods 25 may be passed through the body of the nipple 22 for holding the filtrate in the filter, although these need not be used except at will. 100

In building the well, after digging, the casing is dropped together with the filtering chamber and the foundation built therewith into the opening. As the sands are removed through the opening of the founda- 110

tion the structure gradually descends, giving opportunity to build onto the casing above. Then the foundation finally strikes bed rock, and the opening is cemented or otherwise closed to prevent the incoming of sands, when the caps 20 are removed, the filters applied and the water may then surge into the well.

Having thus described this invention, I 10 claim:

1. A casing, a filtering chamber having a dividing wall, filtering material in the chambers of the filtering chamber, an inlet, having access to one chamber, and outlet 15 from another and into the casing, retaining bars associated with the inlets and outlets, and filtering devices in association with the outlets.

2. A casing, an annular filtering cham-

ber having an annular dividing wall, forming annular chambers within the chamber, a series of inlets having access to one chamber, a series of outlets from another chamber and into the casing, retaining bars associated with the inlets and outlets, and filtering devices in association with the outlets. 25

3. A casing, an annular filtering chamber at its base, a series of inlets to the chamber, a filtering material, a series of outlets from the chamber, said inlet and outlet being on opposite sides of the filtering material, and filtering devices in association with the outlets. 30

Signed at Oklahoma City, in the county 35 of Oklahoma, and State of Oklahoma, this 2nd day of September, in the year 1913.

ALFRED E. WALKER.
